CLAIM

The ornamental design for a unitary filter and cover for animal cages, as shown and described.

DESCRIPTION

FIG. 1 is a top plan view of a unitary filter and cover for animal cages showing my new design;

FIG. 2 is a bottom plan view thereof;

FIG. 3 is a side elevational view thereof, the opposite side being identical to the side shown;

FIG. 4 is an end elevational view, the opposite end being identical to the end shown; and

FIG. 5 is a top perspective view thereof.

The broken line representation of a cage is for illustrative purposes only and forms no part of the claimed design.

FIG. 1

FIG. 2

FIG. 3

FIG. 4

FIG. 5
